HOWARD M. HUNT, OF HUNTINGTON PARK, CALIFORNIA, ASSIGNOR TO SMOOT-HOLMAN CO., OF INGLEWOOD, CALIFORNIA

COMBINATION DRIP PAN AND BAFFLE MEMBER FOR REFRIGERATING CASES

Application filed July 11, 1928. Serial No. 291,732.

My invention relates to combination drip pan and baffle member for refrigerating cases, and it has for its primary object to provide an efficient drip pan and baffle member to be suspended or supported under the coils in a refrigerating case, whereby to catch the drippings from said coils and also to control and stimulate circulation of the air within said case.

10 In order to fully explain my invention, I have shown in the accompanying sheet of drawings a cross sectional view through a refrigerating case with refrigerating coils and my combination drip pan and baffle member, which I will now describe.

Figure 1 is a cross vertical section through a refrigerating case, with my invention shown in connection therewith;

15 Figure 2 is a fragmentary, enlarged view of a portion of the invention; and

Figure 3 is a view similar to Fig. 1, but showing a modified arrangement.

It will be understood that my invention can be applied or used in any case or cabinet 25 where refrigerating coils are used and where it is desired to catch the drippings from the coils and to direct or control the circulation of the air within said case.

In the drawings, 3 designates a refrigeration case, with the glass front 4, and the rear slide doors 5, which can be of any usual or desired construction.

30 In the upper part of the case are supported the refrigerating coils 6, supported or suspended from the top of the case by means 35 of straps 7. Any number of coils and any arrangement and means of support can be used as may be most convenient for the particular design of case or cabinet.

40 My invention consists of a combination drip pan and baffle member, designated 8, with the low wall 9 along one side and with the high wall or baffle member 10, extending along the opposite side, said pan extending 45 lengthwise of the case or cabinet in which it is placed. It will be noticed that the high wall or baffle member 10, extends to a position near the inclined front wall of said case, so as to leave a relatively narrow throat or 50 opening between the upper edge of said wall

and the front wall of the case. It is known that cold air settles or moves downwardly and that the warmer air rises, and if the opposite sides of the pan 8 were low and of the same height, then the cold air from around the coils 6 would simply move downwardly to the pan and then out over the opposite sides thereof in opposite directions. But by providing one wall of said pan higher and carrying it to near the top of the case, 60 the cold air from the coils moves downwardly and outwardly over the lower side of said pan and away from the higher wall or baffle member 10, and this movement of the cold air causes the warmer air to flow upwardly 65 and inwardly through the throat at 11, as indicated by the arrows, and this stimulates or directs the circulation of the air within the refrigerating case. The throat or restricted opening between the top edge of the 70 member 10 and the front of the case front 4, thus operates to cause an accelerated movement of the warmer air to fill in around the coils as the colder air therefrom moves downwardly and outwardly over the lower 75 wall 9 of said pan.

In order to properly protect the drip pan, I coat it with tar or asphalt 12, then apply a layer of tar paper 13, further coated as at 14, then fill in a pressed cork filler 15, with 80 another coat of tar 16, another layer of tar paper 17, and a top covering of karnack, or burlap treated with asphalt or other water proofing matter 18, with a final coat of tar 19. This makes said drip pan water-proof 85 and prevents any possibility of rust or damage thereto on account of the condition within said case. The outside of said pan and baffle member are preferably of baked enamel. It will be understood, of course, that any 90 suitable structure can be used for said pan and baffle member, and that any suitable means for covering and protecting it can be used. It is also provided with a drain opening at its lower side and at one end, or otherwise, as may be desired. A drain outlet is indicated at 20.

In Fig. 3 I have shown an arrangement with two groups of refrigerating coils, 21, 21, with the opposite outer sides provided 100

with baffle structures or louvers 22, 22, for directing and regulating the circulation of the air within the case. When the machine is operating and the circulation is stimulated, 5 the cold air passes downwardly in the middle and some of it will possibly pass out through the lower of the openings, designated 23, 23, but when the machine is not being operated, then the warmer air passes upwardly along 10 the outer sides of said structures and inwardly through said openings 23, 23, and down through the center, after passing over the pipes. This warmer air will also operate to defrost the lower pipes and pans and prevent 15 accumulation of the frost products or ice on said lower pipes and pans beyond what is intended, the defrosting being accomplished periodically in a relatively short length of time during the idle time of the refrigerating machine by the warm air from the food compartment passing through the louvers of the baffles and between the coils. The drip pans are designated 24, 24 in this form of the invention.

25 I do not limit my invention to the exact details here shown for descriptive and explanatory purposes, except as I may be limited by the hereto appended claims, realizing that changes in details of construction and arrangement can be made within the scope of the invention.

I claim:

1. In combination with a refrigerating case having a restricted and tapering top portion and refrigerating coils therein, of baffle means along one side of said coils for directing air outside of said coils upwardly over the top of said coils and downwardly therethrough in direct contact therewith, said 35 baffle means having openings therethrough at different levels opposite said coils, substantially as described.

2. In combination with a refrigerating case and refrigerating coils therein, of drip pans 45 under said coils and spaced apart horizontally to provide a down passage therebetween, vertical walls outside of said coils with openings therethrough for directing air currents from the outer opposite sides of said coils 50 inwardly through said walls, in direct contact with said coils and downwardly through said down passage between said pans.

3. A refrigerating case having a narrower 55 top lengthwise thereof and tapering downwardly and outwardly therefrom, a bank of cooling coils lengthwise in said top portion, a drip pan thereunder to catch drippings and condensations from said coils, a vertical wall 60 along one side of said coils only and terminating near the top to form a restricted throat along the upper edge of said wall and said top to cause warmer air to pass upwardly around the outside of said wall and coils and through 65 said throat and downwardly among said coils

and out and downwardly at the opposite side of said coils and around the opposite side of said drip pan, the contact of said warmer air with said cooling coils operating to cool the air and to cause defrosting of said coils when 70 the machine is periodically idle.

4. A refrigerating case having its top of tapering form to provide the inside top of restricted form with tapering wall, a bank of cooling pipes in said restricted top of said case, a drip pan supported under said pipes, a vertical member from one side of said drip pan upwardly along side of said pipes and terminating near the top to form a restricted throat along the upper edge of said wall and 75 said top to cause warmer air to pass upwardly around the outside of said wall and coils and through said throat to said coils, said vertical wall being provided with a series of longitudinally extended louvers to permit 80 passing of warmer air inwardly and of cold air outwardly through said vertical wall along one side of said cooling pipes, substantially as and for the purpose described.

5. In combination with a refrigerating case 90 and a bank of refrigerating coils therein, of means at one side of said coils for dividing the up-current of air and directing it at different levels over and down among said coils in direct contact therewith, whereby to create 95 definite circulation upwardly and inwardly of the warmer air and directing it down through the refrigerating coils, the opposite side being open for the free passage of air downwardly.

Signed at Los Angeles, Los Angeles County, California, this 25 day of June, 1928.

HOWARD M. HUNT.
